UNITED STATES PATENT OFFICE.

MAX KRAUT, OF SAN FRANCISCO, CALIFORNIA, ASSIGNOR TO JOSEPHINE KRAUT, OF SAN FRANCISCO, CALIFORNIA.

PUMP.

Application filed August 26, 1926. Serial No. 131,606.

This present invention relates to a pump of the centrifugal type, wherein positive pressure is maintained during its operation, and the same is designed to efficiently handle 5 gritty and slimy material which is at present difficult to handle in the ordinary type of either centrifugal or positive pressure pump, due to its liability of cutting out the bearings.

One of the principal objects of this invention is to provide a construction so designed as to prevent while in operation the gritty material from working into the bearings, thus obviating the rapid wearing of the bearings and destruction of the bearings and shaft from 15 this cause.

Another object is the designing of a pump to handle gritty or slimy material containing air or gases in the solution, the pump being so designed as to reduce to a minimum the liability of the same becoming air bound; to provide a pump the shaft of which is capable of being disposed either horizontally or vertically, and when in either position, the operation of the runner of which precludes the 25 gritty material from attacking the bearing or shaft.

Other objects are the designing of a simple and economical construction arranged to permit a ready and quick replacement of worn 30 parts or the adjustment thereof, and to provide a pump wherein is utilized to the fullest extent the power applied towards its object.

With the above mentioned and other objects in view, the invention consists in the novel construction and combination of parts hereinafter described, illustrated in the accompanying drawings and pointed out in the claims hereto appended; it being understood 40 that various changes in the form, proportion, size and minor details of construction within the scope of the claims may be resorted to without departing from the spirit or sacrificing any of the advantages of the 45 invention.

Referring to the drawings forming a part of this application—

Fig. 1 is a longitudinal central sectional view through the preferred embodiment of 50 my apparatus.

Fig. 2 is a view in elevation of the runner

provided with the conical end, and illustrated as being removed from the casing.

Fig. 3 is a vertical sectional view through the runner taken on lines 3—3 of Fig. 1. 55

Fig. 4 is a vertical sectional view taken on line 4—4 of Fig. 1.

In the drawings, wherein like characters of reference designate corresponding parts throughout the several views—1 is a base upwardly from which extend the bearing arms 2 and the shell supporting arm 3. The arm 3 mounts a cylindrical runner shell 4 having a flanged edge 5, and connected with said runner shell 4 is a hollow conical shell body 6 inwardly from the inner surface of which, toward the center of the runner shell 4, extends a cylindrical flange 7. The shell body 6 and flange 7 are attached in any suitable manner to the center bearing arm 2, as in Fig. 1. 60 70 65

Extending concentrically from the center bearing arm 2 and through the shell body 6 and runner shell 4 is a bearing sleeve 8 carrying at its opposite ends the bearings 9 and 10. The bearing arm 2 at its upper end also carries a bearing 11 in line with the bearings 9 and 10, and in said bearings is rotatably mounted a power shaft 12 carrying a power pulley 13 between bearings 9 and 11. The shaft 12 extends through the sleeve 8, as illustrated in the drawings. 75 80

Communicating with the shell body 6 is a fluid inlet 14, the same discharging into the space 15 between the sleeve 8 and flange 7, and the fluid passing endwise from said space through a number of openings 16, illustrated in detail in Figs. 3 and 4. 85

Bolted to the flange 5 of the cylindrical runner shell is a conical shell extension 17, the apex of which is provided with a discharge opening 18 to the flange 19 of which is bolted the elbow of a discharge pipe 20. 90

Keyed as at 21 to the end of the shaft 12 and positioned within the conical shell 17 is a hollow conical runner extension 22, the peripheral surface of which lies parallel with the inner surface of the shell 17 and carries a plurality of helical ribs 23 extending from the apex to the base thereof. The extension 22 at its base is secured to the side wall 24 of a cylindrical runner 25 of the conventional closed type. The runner 25 rotates within the 100

shell 4 as in Fig. 1, and between its walls 24 and 26 is provided with the usual blades 27, the inlet thereto being through the openings 16 into the center of the runner and the discharge therefrom being peripherally of the runner between the walls 17 and 22. From the rear face of the runner shell wall 26 extends a flange 28 disposed parallel with the wall 6 and provided with a flange 29 disposed parallel with the wall 26 of the runner. The wall 24 adjacent the inner periphery of the conical extension 22 is provided with a plurality of spaced drain ports 30, Fig. 1. The inner surface of the wall of the extension 22 is substantially parallel with the outer surface and flares towards the base of the conical shell.

In operation, the pipe or inlet 14 is connected with the fluid supply to be pumped and the elbow 20 to a place of deposit or delivery to receive the pumped material. The pulley 13 is rotated to revolve the runner 25 in the direction of the arrow, Fig. 3, and such movement causes a rapid rotation of the runner 25 and its conical extension 22. This action causes the fluid to enter the space 15 and through openings 16 to pass into the runner 25. The velocity and centrifugal force imparted to the fluid by the vanes 27 forces the fluid towards the periphery of the runner and through the annular space between the base of the conical extension 22 and the peripheral wall of the runner 25, where it is picked up by the helical ribs 23 and conveyed towards the apex of the shell 17 in the space between the walls 17 and 22.

The positive action of the members 23 in picking the liquid or fluid up from the periphery of the runner prevents the pump from becoming air bound, as this action forces the liquid from the periphery of the runner longitudinally of the conical extension towards its apex. This conversion of velocity head into pressure head is thus very gradual and positive, the pressure increasing towards the apex of the conical extension 22 as the peripheral velocity decreases.

By making the conical extension 22 hollow, as illustrated, any pumped liquid which may enter the same, is when the runner 25 is rotated, forced on the inner surface of the flaring conical extension towards the apertures 30 and finds its way immediately back into the runner near its periphery and partakes in the flow of the incoming feed. If the runner is at a point of rest, the conical extension will immediately empty itself on rotation being imparted to the runner, thus the tendency is to maintain the bearing 10 clear of the pumped fluid at all times during the operation of the device.

Should it be desired that the installation be mounted with the shaft 12 in a vertical position and the runner 25 carried by the upper end thereof, the flow of fluid into the hol-

low portion of the conical extension 22 will be precluded by the intrapped air in the upper end of this extension.

It will be readily apparent that it is the combination of the hollow conical extension 70 from the runner operating within the conical shell, and the provision of the fluid inlet centrally of the runner and the outlet at the apex of the shell that enables the objects of this present invention to be attained. 75

I claim:—

1. A pump comprising a pair of concentrically disposed hollow conical members arranged with their adjacent wall surfaces lying in spaced relation forming a fluid passage and the inner surface of the wall of the inner member flaring toward its base, a shaft projecting into the hollow portion of the inner of said members and rotatably mounting the same, a bearing for said shaft located 85 within the hollow portion of said inner hollow member, a fluid outlet leading from the apex of the outer of said members, a pump runner at the base of the inner member provided with a center inlet and a peripheral discharge, the latter communicating with one end of the fluid passage, a connection between the inner wall surface of the inner member and the runner, a runner casing provided with a fluid inlet, a helical rib carried by the 95 inner of said conical members, and means for rotating the conical member mounting said rib.

2. A pump comprising a conical shell provided at its apex with a fluid outlet, a conical member rotatably mounted within said shell with its wall in spaced relation to the shell wall, a helical rib carried by the conical member and extending from its base to apex, means for feeding fluid under pressure to 105 the base of the conical member, and a bearing for said rotatably mounted conical member concealed within the conical member, the rotation of the conical member maintaining the fluid pumped in a moving direction away 110 from said bearing.

3. A pump comprising a conical shell provided at its apex with a fluid outlet, a hollow conical member rotatably mounted within said shell with its wall in spaced relation to the shell wall, a helical rib carried by the conical member and extending from its base to apex, means for feeding fluid under pressure to the periphery of the base of the conical member, and means for rotating the conical member, the inner wall surface of the hollow conical inner member flaring toward said fluid feed whereby fluid entering the inner hollow conical member is discharged by centrifugal action from its base. 120 125

4. A pump comprising a conical shell provided at its base with a fluid inlet and at its apex with a fluid outlet, a tubular bearing sleeve extending axially into said shell and terminating short of its apex, a hollow conical 130

inner member rotatably mounted within said shell with its wall in spaced relation to the conical shell wall and overlying the tubular sleeve, a shaft rotatable in the bearing 5 sleeve and mounting the hollow conical member at a point inwardly removed from its apex, the inner wall surface of the hollow

conical inner member flaring toward its base and communicating with the fluid inlet, and a helical rib carried by the surface of the inner 10 conical member.

In testimony whereof I have signed my name to this specification.

MAX KRAUT.
